UNITED STATES PATENT OFFICE.

CHARLES WILLMS, OF BALTIMORE, MARYLAND.

RHEOSTAT.

SPECIFICATION forming part of Letters Patent No. 475,528, dated May 24, 1892.

Application filed January 14, 1892. Serial No. 418,036. (No model.)

To all whom it may concern:

Be it known that I, CHARLES WILLMS, a citizen of the United States, residing at Baltimore, in the State of Maryland, have invented 5 certain new and useful Improvements in Rheostats, fully described and represented in the following specification and the accompanying drawings, forming a part of the same.

The object of the present invention is to 10 improve the construction of rheostats or current-regulators, and especially to provide an improved resistance material therefor. I have devised, also, an improved rheostat employing my improved resistance material and 15 a method of making the same, which forms part of the present invention.

It is desirable that the resistance material used in rheostats should be of considerable 20 resistance and at the same time have sufficient conductivity for the purposes for which the rheostat is designed. Such resistance materials are commonly formed of conducting material in a state of fine division, and while various materials are used for this purpose, 25 pose finely-divided carbon, in the form of lamp-black or graphite, has been found satisfactory and is now in general use, being usually mixed with glue or other material to form a mass of the required density.

I provide an improved resistance material 30 in which the desired relations between resistance and conductivity are better attained than in resistance materials previously in use by mixing with a resistance material containing 35 finely-divided carbon or other suitable finely-divided conducting material particles somewhat larger than those of the conducting material and of high conductivity. I may use as the larger particles filings of copper, brass, 40 or similar metal of high conductivity; but it will be understood that similar particles of other material may be used—such as granular carbon—and that the particles may be produced by any other method than filing, 45 the particles being described as “filings” only to indicate approximately their preferred size.

My improved resistance material is of general application in rheostats, and it may be 50 formed and applied in any suitable manner; but the invention has been made in connec-

tion with that class of rheostats used for light currents in which the body of resistance material consists of a thin layer of plastic material, and I have devised a special method of 55 forming this by which this body of resistance material is rendered more durable, the tendency to crack and peel off is lessened, and by which the resistance material may be more readily applied to form a uniform body of the 60 slight thickness required.

The method I employ in forming my rheostat is as follows: I first paint upon the body of the rheostat a base of the same shape as the body of resistance material desired, this 65 base consisting of a mixture of adhesive material and finely-divided carbon, preferably in the form of graphite, and upon this base I sift, preferably by shaking it from an ordinary pepper-box, the required amount of 70 metal filings or other similar particles of high conductivity. I then subject the rheostat to pressure and thus force the metal filings into and through the body of the base, so as to form a resistance material uniform throughout. The form of the adhesive base and the 75 steps necessary in completing the rheostat depend upon the particular form of rheostat with which my resistance material and method are employed.

In forming the adhesive base I may use glue or any other suitable adhesive material, and with adhesive materials of a certain consistency the method may be varied by applying the adhesive material alone to form the base 85 and completing the resistance material by sifting over and pressing into it a mixture of the finely-divided carbon and the larger particles. I have found, however, that the best results are attained with sugar-water, with 90 which the fine carbon, preferably in the form of powdered graphite, is mixed to form a mixture of the consistency of paint. This is applied with a brush to the face of the plate, the number of coats being varied with the 95 thickness of resistance material desired. The larger particles are then added and the body of resistance material completed, as already described. The sugar-water possesses many advantages over glue, the most important of 100 which is that the body of resistance material formed thereby is much tougher and harder

and resists better the action of heat, which feature is very important with heavy currents.

For a full understanding of my invention a 5 detailed description of a rheostat embodying the same will now be given, and the features forming my invention specifically pointed out in the claims.

In the accompanying drawings, forming a 10 part of this specification, Figure 1 is a plan view of the rheostat. Fig. 2 is a reverse plan of the same. Fig. 3 is a section on the line 3 of Fig. 1, and Fig. 4 is a section on the line 4 of Fig. 2.

15 Referring to said drawings, A is a block of insulating material, preferably of rubber, and a b the binding-posts mounted thereon and forming the terminals. The binding-posts a b pass through the block A and connect, re- 20 spectively, with metallic contact-plates c d, secured to the under side of the block. The plate c forms the contact-plate from which the current passes through the insulating material, and the plate d connects by means of a 25 stud e, extending through the block, with a contact-arm f, moving in the arc of a circle over the top of the block and actuated by means of an insulating thumb-piece g, connected to the stud e and arm f by a cross-pin, 30 as shown, or in any other suitable manner. The contact-arm f at its outer end moves over and makes contact with a series of conductors, consisting in the form shown of pins h, 35 preferably level with the top of the block A and extending through the same. While the conductors are shown as pins and as of the same size on both sides of the block, it will be understood that they may be of any other suitable construction and that the area of 40 their surface on the under side of the block may be increased in any suitable manner if a wider conducting-surface in contact with the resistance material be desired. The conductors h extend about the block in the arc 45 of a circle, which is shown in the drawings as nearly complete; but it will be understood that the length of the arc may be varied, as desired, and may be any portion of a circle, and that the circular form is not essential, 50 but is adopted simply on account of convenience in making contact with a single point through an arm swinging in the arc of a circle.

The resistance material i is shown as applied in a path of decreasing width from the 55 contact-plate c through the circuit of the conductors h, as usual in this class of rheostats, so that by the movement of the arm f over the pins a greater or less length of the resistance material may be thrown into the circuit, 60 the resistance increasing as the width of the path of resistance material diminishes, and the current being conveyed through the resistance material and that one of the conductors h with which the arm f is brought 65 into contact to binding-post a to complete the circuit. With the small current used with

rheostats of this construction a comparatively thin body of resistance material is required, and much difficulty has been found in producing a uniform layer of resistance material, and such rheostats have not been durable on account of the tendency of the resistance material to crack and peel off. 70

In carrying out the method forming a part 75 of the present invention in the preferred manner I first paint upon the under side of the block A a mixture of adhesive material and finely-divided conducting material, preferably carbon, in the form of powdered graphite, to form a picture of the body of resistance material to be applied and to cover the conductors and contact-plate c, this mixture forming a base closely adherent to the block and plate, so that the resistance material is firmly secured thereby. Upon this base I shake from 80 an ordinary pepper-box or similar box the required amount of metal filings or similar particles of some material of high conductivity, so as to entirely cover the base. I then submit the rheostat to pressure, by which the 85 carbon and metal filings are forced into and intimately mixed with the base to form the resistance material and the loose particles are then dusted off. As above stated, the adhesive material used in forming the base by this 90 method is preferably sugar-water or some equivalent thereof, although other adhesive materials may be used with fairly good results.

95 In the modified method above described, in which the base is formed of adhesive material alone, I apply the adhesive material to the face of the block without covering the pins h and plate c, and then sift over it a mixture of finely-divided conducting material— 100 such as powdered graphite and the metal filings or similar particles—and then press these materials into the glue and dust off the loose particles, as before. If care has been 105 taken in applying the base, it is now necessary for the completion of the rheostat only to cover the conductors h and the plate c with a compound of graphite and adhesive material, and then dust over this material the metal filings, this also being preferably submitted to pressure so as to consolidate the 110 filings and resistance material. It will probably be more convenient, however, to apply the base without regard to the conductors 115 h and plate c, so that a resistance material 120 extending over the whole surface of the block between the pins and about the plate shall be secured. When this is done, however, it is evident that the adhesive material forms a layer between the resistance material proper 125 and the conductors and plate which would interfere with the conduction of the current. I therefore in carrying out my method scrape off the material from the conductors and plate after the body of resistance material has been applied to the block, as above described, and then apply to the conductors and plate the com-

pound of graphite and adhesive material, sifting the metal filings over this and pressing in the same, as above explained.

While I have illustrated my invention as applied to a special form of rheostat employing a thin layer of resistance material, it will be understood that my improved resistance material is of general application in rheostats, independently of the thickness of the body of resistance material, and may be made and applied in any other manner than that described, and that my improved method of forming the body of resistance material may be applied to rheostats of other construction than that shown.

What I claim is—

1. An adhesive resistance material for rheostats, containing adhesive material, finely-divided conductive material, and metal filings or similar particles of high conductivity, substantially as described.
2. The method of forming the body of resistance material in rheostats, which consists in forming an adhesive base of the form of the body of resistance material desired, sifting thereon particles of conducting material, and combining the conducting material with the adhesive base by pressure, substantially as described.
3. The method of forming the body of resistance material in rheostats, which consists in applying a mixture of adhesive material

and finely-divided conducting material to form a base of the form of the body of resistance material desired, sifting thereon metal filings or similar particles of high conductivity, and combining these particles with the adhesive base by pressure, substantially as described.

4. The method of forming the body of resistance material in rheostats, which consists in applying a mixture of sugar-water or equivalent material and finely-divided conducting material to form a base of the form of the body of resistance material desired, sifting thereon larger particles of conducting material, and combining the conducting material with the adhesive base by pressure, substantially as described.

5. A rheostat having a supporting block of non-conducting material and a body of resistance material secured to the face thereof by adhesive material and containing finely-divided conducting material and larger particles of metal or other material of high conductivity, substantially as described.

In testimony whereof I have hereunto set my hand in the presence of two subscribing witnesses.

CH. WILLMS.
